UNITED STATES PATENT OFFICE.

RICHARD FUTRAL, OF ST. LOUIS, MISSOURI, ASSIGNOR TO ST. LOUIS STOVE COMPANY,
OF ST. LOUIS, MISSOURI, A CORPORATION OF MISSOURI.

STOVE.

Application filed September 11, 1922. Serial No. 587,346.

To all whom it may concern:

Be it known that I, RICHARD FUTRAL, a citizen of the United States, residing at St. Louis, Missouri, have invented a new and useful Stove, of which the following is a specification.

This invention relates to improvements in stoves, and more particularly to an attachment to be mounted in the upper part of the combustion chamber of the stove for the purpose of deflecting the flame and products of combustion, whereby the walls of the stove are heated to a greater degree.

An object of the invention is to provide an attachment for stoves comprising a deflector plate arranged to deflect the products of combustion before the same enter the outlet flue of the stove.

Another object of the invention is to provide an attachment for stoves comprising a horizontal deflector wall with a vertical wall so positioned in connection therewith as to provide a lateral flue outlet from the combustion chamber between the combustion chamber and the normal flue outlet of the stove.

Additional advantages of the construction will be apparent from the detailed description thereof taken in connection with the accompanying drawing, in which—

Fig. 1 is a plan view of the stove with the attachment embodied therein.

Fig. 2 is a vertical section further illustrating the construction of the attachment.

Fig. 3 is an isometric view of the attachment detached from the stove.

The invention is shown embodied in a stove including a drum 1 forming the combustion chamber of the stove, below which is supported a grate 2 mounted above an ash pit 3; the stove being supported by legs 4. The drum is provided with a top member 5 having adjacent to the back thereof an outlet flue 6 and having an opening in the front of the top covered by a lid 7. In the embodiment illustrated in the drawing the attachment is shown as applied to a stove having a substantially cylindrical drum, although it will be understood that it may be applied to any stove of the general type comprising a combustion chamber having a direct flue outlet located in the top of the stove forming a direct draft.

A stove of this type has the disadvantage

of not obtaining the maximum heat from the products of combustion, for the reason that the gas generated in the stove form a cone, the apex of which is the outlet opening of the flue. Much of the heat from the fuel is thus carried directly through the flue without heating the side walls of the combustion chamber.

The attachment of the present invention obviates the above disadvantage by providing a deflector device causing the normal cone formed by the products of combustion to be deflected at the top and against the side wall of the combustion chamber.

The device of the invention consists of a substantially semi-circular plate 8 arranged to be mounted in the upper part of the combustion chamber parallel with the top of the stove and spaced therefrom, the plate being substantially semi-circular in form covers approximately half of the cross area of the combustion chamber and constitutes a deflecting plate preventing direct passage of the products of combustion to the outlet flue. The plate 8 may be attached to the side wall of the drum in any suitable manner and a convenient method is to provide a series of depending lugs 9 on the edge of the plate 8 through which bolts 10 extend, thereby supporting the plate rigidly in place. Adjacent to the front edge of the plate 8 is a vertical plate 11. The plate 11 has hinge connections 12 with the upper wall of the plate 8 and is provided with a damper rod 13 extending out through the side wall of the drum, so that the plate 11 may be manipulated from a vertical position to a flattened position against the upper wall of the plate 8. The purpose of the adjustment of the plate 11 is to increase or decrease the outlet area over the front edge of the plate 8 at will.

It will be noted that the plate 11 is of a length less than the length of the front edge of the plate 8, so that there is provided on either side of the plate 11, when said plate 11 is in a vertical position, supplemental outlet flues 14 through which the products of combustion are required to pass before entering the outlet flue 6 of the stove. In Fig. 2 arrows diagrammatically illustrate the deflection of the products of combustion caused by the attachment of the device of the invention, from which it will be understood that the volume of gas and products of com-

bustion are deflected to the outer portion of the combustion chamber and against the drum of the stove.

In the normal operation of the device the plate 11 is maintained in upright position. When in this position the joint cross area of the outlets 14 are approximately equal to the cross area of the main outlet flue 6.

It has been found in practice that, by proportioning the outlet openings so that the openings 14 equal the outlet opening 6, the best results are obtained. If it is desired to increase the draft by manipulating the damper rod 13 the plate 11 may be laid back 15 against the upper face of the plate 8, providing a more direct outlet to the flue 6.

I am aware that the invention may be modified in certain particulars without departure from the spirit and scope thereof.

I do not limit myself unessentially, but what I claim and desire to secure by Letters Patent is:—

1. In a stove, the combination with a drum, of a grate, a top supported by the drum, a flue outlet from the top near the back thereof, a plate extending across approximately half of the drum near the top thereof thereby forming a compartment at the top of the combustion chamber, and a vertical plate connected with the front edge of said first-named plate, the ends of said last-named plate being spaced from the drum thereby forming outlet openings whereby the products of combustion are deflected at the top of the combustion chamber.

2. In a stove, the combination with a drum, of a grate, a top supported by the drum, a flue outlet from the top near the back thereof, a plate extending across approximately half of the drum near the top thereof thereby forming a compartment at the top of the combustion chamber, and a vertical plate connected with the front edge of said first-named plate, the ends of said last-named plate being spaced from the drum thereby forming outlet openings, the cross area of said outlet openings being approximately equal to the cross area of the first-named flue outlet.

3. In a stove, the combination with a drum, a grate, a top for the drum, a flue outlet opening adjacent to one edge of the top, of a substantially semi-circular plate mounted in the drum masking approximately half of the upper part of the combustion chamber below the flue outlet opening, and a vertical plate positioned at the

front edge of said last-named plate and extending adjacent to the under face of the top of the stove, said vertical plate being spaced at its ends from the side wall of the drum to form outlet flue openings at each side of the main flue outlet.

4. In a stove, the combination with a drum, a grate, a top for the drum, a flue outlet opening adjacent to one edge of the top, of a substantially semi-circular plate mounted in the drum masking approximately half of the upper part of the combustion chamber below the flue outlet opening, a vertical plate positioned at the front edge of said last-named plate and extending adjacent to the under face of the top of the stove, said vertical plate being spaced at its ends from the side wall of the drum to form outlet flue openings at each side of the main flue outlet, a hinge connection between the vertical plate and said first-named plate, and a damper rod extending exteriorly of the drum for controlling the position of said vertical plate.

5. In a stove, the combination with a drum, a grate, a top supported by the drum, an outlet flue opening in the top adjacent to one edge thereof, of a plate positioned below the top, said plate being of an area less than the top, the space between the plate and grate being open and unencumbered and cooperating with the top and with the drum to form a compartment, a partition plate connected with the inner edge of said first-named plate, the ends of said partition plate being spaced from the walls of the drum, a hinge connection between said partition plate and said first-named plate whereby said partition plate may be moved from a vertical position in respect of said first-named plate to a position against the upper face thereof for the purposes specified.

6. In a stove, the combination with a drum, a grate, a top supported by the drum, an outlet flue opening in the top adjacent to one edge thereof, of a plate positioned below the top, said plate being of an area less than the top, the space between the plate and grate being open and unencumbered and cooperating with the top and with the drum to form a compartment, and a partition plate connected with the inner edge of said first-named plate, the ends of said partition plate being spaced from the walls of the drum.

RICHARD FUTRAL.
